UNITED STATES PATENT OFFICE.

WILLIAM M. BACON, OF CHICAGO, ILLINOIS, ASSIGNOR TO ENAMELED STEEL SIGN COMPANY, OF CHICAGO, ILLINOIS, A CORPORATION OF ILLINOIS.

PRINTING-MACHINE.

1,385,654.

Specification of Letters Patent. Patented July 26, 1921.

Application filed March 29, 1920. Serial No. 369,460.

To all whom it may concern:

Be it known that I, WILLIAM M. BACON, a citizen of the United States, residing at Chicago, Cook county, Illinois, have invented a new and useful Printing-Machine, of which the following is a specification.

This invention relates to improvements in printing machines, and more particularly to feeding and delivering devices for such machines.

An object of the invention is to provide improved sheet feeding and delivering devices for feeding sheets of metal, wood, cardboard, or fabric to the printing mechanism of the machine and delivering them after the impressions have been received thereon.

The specific improvements will be readily understood from the following detailed description taken in connection with the accompanying drawings, in which—

Figure 1 is a broken plan view of the printing machine embodying the invention.

Fig. 2 is a broken side elevation of the machine.

Fig. 3 is a cross section through the machine.

Fig. 4 is a detailed view illustrating the guiding mechanism for feeding the work between the printing cylinders after it has been moved toward the printing point by the feeding mechanism.

In the embodiment of the invention illustrated in the drawings the machine comprises an open metal frame including corner standards 1 preferably composed of angle iron, said standards supporting a lower rectangular frame 2 and an upper frame 3. Approximately centrally disposed and rising at the side of the frame are heavy standards 4 constructed preferably of I-beams.

The motor M for operating the machine is mounted on a standard 5 extending transversely of the machine and carried by the side members of the lower frame 2.

Extending transversely and lying within the frame is a cylinder 6 supported upon a shaft 7, the shaft 7 being journaled at each end in movable bearings 8 slidably mounted in openings 9 in the web of standards 4.

The bearings 8 are raised and lowered by bearing adjusting mechanism of known construction which is operated by the hand rod 10. The cylinder 6 constitutes the platen upon which the work is fed to receive printing impressions from the printing roller.

As it is desirable to adapt the machine to receive material of various thicknesses and to adjust the pressure of the work against the printing cylinder, the machine has been arranged so that by the operation of the hand rod 10 an extremely accurate adjustment of the shaft 7 may be effected.

The type cylinder 11 is carried on a shaft 12 which is journaled at each end in permanently adjusted bearings 13 mounted at the top of the standards 4. The axis of the shaft 12 is in parallel vertical alinement with the axis of the shaft 7 and since the shaft 7 is adjustable vertically the space between the proximate peripheries of the cylinders 6 and 11 may be varied as required for receiving the work at the printing point of varying thickness, so that regardless of the thickness of the work a uniform pressure is exerted thereon to effect the printing as it passes between said cylinders 6 and 11 at the printing point. The mechanism for rotating the cylinders 6 and 11 in synchronism comprises a pinion 14 attached to the drive shaft 15 of the motor which extends beyond the frame work at one side of the machine. The pinion 14 meshes with and drives a large gear wheel 16 which is fast on an extended end of the shaft 7.

An intermediate pair of gears are arranged in a movable bearing 17, said movable bearing being supported at the junction of links 18 and 19, the outer ends of which are respectively pivoted upon shafts 7 and 12. The pair of intermediate gears 20 are mounted upon a common shaft 20 which is revolubly mounted in the adjustable bearing 17. The pair of gears are in parallel vertical planes and the inner one 21 of said gears meshes with the large gear 16 and the outer one 22 of said pair of gears meshes with a gear 23 which is mounted upon the link 19, the gear 23 in turn meshing with and driving a gear 24 secured to an extension of the shaft 12. The gear 24 has a releasable connection with the shaft 12 in the form of an adjustable cone clutch 25 of known construction. The gear 24 is arranged so that it may be rotated in adjusting operations without rotating the shaft 12 and thereby the cylinder 11, so that after the adjustment is effected the gear wheel may be locked to the shaft 12.

It will be observed that the drive connection whereby the shaft 12 is driven permits

the elevation of the axis of the shaft 7 to be changed without throwing out of mesh the driving connection between the two cylinders. Obviously, as the shaft 7 is lowered 5 the axes of the pair of gears 21 and 22 is drawn inwardly, preserving the meshing engagement between the gear 21 and the gear 16, the normal adjustment of the axes of the gears 22 and 23 and between the axes 10 of the gear 23 and 24. By this arrangement it will be seen that the two cylinders 6 and 11 may be driven in synchronism regardless of the adjustment of the shaft 7 upon which the cylinder 6 is supported.

15 The mechanism for feeding the work to the printing point between the cylinders comprises an endless belt or chain 26 which operates over alined sprockets 27 and 28, said sprockets being carried respectively by 20 shafts 29 and 30 journaled in bearings 31 and 32 on the upper face of the frame 3. The shaft 29 is disposed near one end of the frame and the shaft 30 is arranged in parallel alinement therewith but near the 25 printing cylinders. The sprockets 27 and 28 are arranged so that the endless belt or chain 26 extends longitudinally with the frame of the machine at a position intermediate of the width of the machine. At one 30 side of the belt 26 is a series of permanently fixed revoluble rollers 33, said rollers being arranged in supports with the axes thereof parallel in a horizontal plane and inclining forwardly toward the right hand side of the machine. At the right hand side of the belt 35 34 is a second series of rollers 34 which are in a laterally adjustable support comprising side members 35 and end members 36, the end members 36 being adjustably supported 40 by cross bars 37 carried by the frame of the machine. Thus the entire frame in which the rollers 34 are supported may be moved toward and away from the belt 26 so that the feeding mechanism is adapted to receive 45 material of different widths. When the adjustment has been effected the support may be locked in position by set screws 38, which lock the end members 36 of the roller supporting frame with the bars 37. The rollers 50 34 are arranged in the same horizontal plane with the rollers 33 and have their axes inclined outwardly toward the right hand side of the machine at the same angle of inclination as the axes of the rollers 33.

55 At the outer side of the movable frame, in which the rollers 34 are supported, is a vertically disposed guide strip 39 for guiding the edge of the work as it is fed by the feeding mechanism to the printing rollers.

60 The belt 26 carries a number of adjustable lugs 40 which contact with the forward end of the flat sheets of work when the same are placed upon the rollers 33 and 34, and the lugs extend above the horizontal plane of 65 the upper surface of the two sets of rollers.

As the work is moved forwardly by the inward movement of the belt, exerting pressure upon the front edge of the work through the lugs 40, the flat sheets are moved to the right hand side of the machine against the 70 inner face of the guide strip 39 and at the same time fed inwardly toward the printing point. The feeding mechanism thus automatically adjusts the position of the sheets as they are fed to the printing mechanism 75 so that they will be received for printing impressions under proper alinement and adjustment.

Extending inwardly from the forward end of the frames in which the rollers are 80 supported is a guide plate 41 which inclines upwardly at its inner end so that its inner edge will lie in the same horizontal plane with the periphery of the cylinder 6 at the printing point. In Fig. 4 this mechanism is 85 clearly shown from which view it will be observed that a sheet S of the work, after it leaves the roller, is raised by the guide strip 41 to a horizontal plane coincident with the space between the cylinders 6 and 11. The 90 guide strip 41 has sufficient resilience so that when the cylinder 6 is lowered the forward end of the strip will be depressed sufficiently to maintain the adjustment between the periphery of the cylinder at the printing point 95 and the inner edge of the guide strip so that regardless of the adjustment of the cylinder 6, the work will always be presented in the proper horizontal plane to be received between the cylinders 6 and 11 at the printing point. 100

In the rear of the cylinders is a work discharging mechanism comprising a number of longitudinally disposed and parallel alined belts 42 which operate over rollers 105 43 supported on shafts 44 journaled in brackets 45 mounted on the upper face of the frame of the machine. Both the belt 26 and the belts 42 are moved in the same direction, that is from the forward end of 110 the machine toward the rear thereof, by driving mechanism comprising a gear 46 which meshes with the large gear wheel 16, the gear 46 in turn meshing with and driving a pinion 47 fast on the forward one of 115 the shafts 44, thereby rotating said shaft 44. The shaft 44 carries a sprocket wheel 48, and the inner one of the shafts 30 carries a sprocket wheel 49. A belt connection 50 operating over the sprockets 48 and 49 provides a power connection whereby the said shaft 30 is driven from the shaft 44, thus both the feeding mechanism and the discharge mechanism are operated together in 120 the same direction and at the same rate of travel. 125

I am aware that the embodiment of the invention may be modified in various particulars without departing from the spirit and scope of the invention. I do not limit 130

myself therefore to the exact construction shown and described, but what I claim and desire to secure by Letters Patent, is:—

1. In a printing machine, including a main frame, a printing cylinder revolvably mounted above the upper surface of the main frame, a platen located below the upper surface of the main frame, feeding mechanism comprising a series of feed rollers carried in the main frame for supporting flat sheets to be fed between said printing cylinder and said platen, a belt having contact members thereon for moving said sheets on said rollers, and a guide for laterally alining the sheets so that they will be received between the printing cylinder and the platen at a predetermined lateral point.

2. In a printing machine, including a main frame, a printing cylinder revolvably mounted above the upper surface of the main frame, a platen located below the upper surface of the main frame, feeding mechanism comprising a series of feed rollers carried in the main frame for supporting flat sheets to be fed between said printing cylinder and said platen, a belt having contact members thereon for moving said sheets on said rollers, a guide for laterally alining the sheets so that they will be received between the printing cylinder and the platen at a predetermined lateral point, and a guide for elevating the sheets fed from said rollers so that they will be received in the space between the printing cylinder and the platen.

3. In a printing machine, including a printing cylinder and a coördinating platen spaced therefrom, a feeding mechanism comprising an endless belt having contact members thereon adapted to engage sheets of work and to move the same toward the interval between the printing cylinder and said platen, a lateral guide for guiding the work so moved by said feeding belt, a series of rollers for supporting the work and directing the same into marginal engagement with said guide, and a guide device for elevating the work so as to enter the interval between said printing cylinder and said platen to receive the printing impressions.

4. In a printing machine, including a printing cylinder and a coördinating platen spaced therefrom, feeding mechanism comprising an endless belt having contact members thereon adapted to engage sheets of work and to move the same toward the interval between the printing cylinder and said platen, a lateral guide for guiding the work so moved by said feeding belt, a series of rollers for supporting the work and directing the same into marginal engagement with said guide, a guide device for elevating the work so as to enter the interval between said printing cylinder and said platen to receive the printing impressions.

5. In a printing machine, including a

printing cylinder and a platen, said printing cylinder and platen being arranged to receive the work therebetween; a feeding mechanism comprising a series of rollers having their peripheries in the same horizontal plane and approximately in the same plane as the space between the printing cylinder and the platen, said rollers being arranged to guide the work toward one edge of the machine, a guide strip running vertically at one side of said rollers for guiding the work moved thereagainst by the rollers, a continuously operating actuator for moving the work placed upon said rollers toward the interval between the printing cylinder and the platen, and means for driving said printing cylinder, said platen and said feeding mechanism from a common source of power.

6. In a printing machine, including a printing cylinder and a platen, said printing cylinder and platen being arranged to receive the work therebetween; a feeding mechanism comprising a series of rollers having their peripheries in the same horizontal plane and approximately in the same plane as the space between the printing cylinder and the platen, said rollers being arranged to guide the work toward one edge of the machine, a guide strip running vertically at one side of said rollers for guiding the work moved thereagainst by the rollers, a continuously operating actuator for moving the work placed upon said rollers toward the interval between the printing cylinder and the platen, means for driving said printing cylinder, said platen and said feeding mechanism from a common source of power, and a guide at the inner end of said series of rollers for raising the work as it leaves the rollers and directing it into the space between the printing cylinder and the platen.

7. In a printing machine, including a printing cylinder and a platen, said printing cylinder and platen being arranged to receive work therebetween; a feeding mechanism comprising two series of rollers having their peripheries in the same horizontal plane and approximately in the same plane as the space between the printing cylinder and the platen, said rollers being arranged to guide the work toward one edge of the machine, a guide strip running vertically at one side of said rollers for guiding the work moved thereagainst by the rollers, a continuously operating actuator for moving the work placed upon said rollers toward the interval between the printing cylinder and the platen, means for driving said printing cylinder, said platen and said feeding mechanism from a common source of power, a guide at the inner end of said series of rollers for raising the work as it leaves the rollers and directing it into the space be-

tween the printing cylinder and the platen, and a device for conveying the work from the machine after it has received printing impressions.

5. 8. In a printing machine, including two cylinders disposed one above the other with an interval therebetween for receiving the work; a feeding mechanism comprising a double series of rollers arranged in longitudinal alinement with an interval therebetween, a moving actuator operating between the rollers having means for engaging the work, a guide disposed at one side of said rollers for preserving the marginal alinement of 10 the work moved toward the printing cylinders by said actuator, and driving mechanism for actuating said cylinders and said actuator from a common source of power.

9. In a printing machine, including a rigid 20 frame, two rotating printing cylinders in the frame, said cylinders being arranged with a space therebetween; feeding mechanism comprising a movable belt having a path of travel toward the space between 25 said cylinders, a rigid support mounted in said frame on one side of said belt, a series of rollers in said frame inclined at an angle so that work placed thereon will be moved toward one side of the machine, an adjustable support 30 on the other side of said belt

having a series of rollers therein disposed in alinement with said first-named rollers, a marginal guide strip for contacting with the edge of the work fed toward the printing mechanism by said belt, and means for 35 effecting lateral adjustment of said last-named support.

10. In a printing machine, including a rigid frame and two rotating printing cylinders arranged with a space therebetween; a 40 feeding mechanism comprising a movable belt having a path of travel toward the space between said cylinders, a rigid support mounted in said frame on one side of said belt, a series of rollers in said frame inclined at an angle so that work placed thereon will be moved toward one side of the machine, an adjustable support 45 on the other side of said belt having a series of rollers therein disposed in alinement with said first-named rollers, a marginal guide strip for contacting with the edge of the work fed toward the printing mechanism by said belt, means for effecting lateral adjustment of said last-named support, and 50 a conveyer on the opposite side of the printing mechanism for conveying the work from the machine after the same has passed between said cylinders.

55 WILLIAM M. BACON.
